207,185

COMBINATION CLOCK-RADIO AND LAMP, OR SIMILAR ARTICLE

Victor Reichenstein, Great Neck, N.Y., assignor to Consolidated Merchandising Corp., New York, N.Y., a corporation of New York

Filed Feb. 9, 1966, Ser. No. 985

Term of patent 7 years

(Cl. D56—4)

FIG. 1

FIG. 2

FIG. 4

FIG. 3

FIG. 5

FIG. 1 is a front perspective view of a combination clock-radio and lamp showing my new design, with the lamp portion shown in elevated and extended position;

FIG. 2 is a front elevational view of the combination clock-radio and lamp, with the lamp portion shown in closed retracted position.

FIG. 3 is a rear perspective view of the combination clock-radio and lamp in the retracted position of FIG. 2;

FIG. 4 is a top plan view thereof; and

FIG. 5 is an end elevational view thereof as viewed from the direction of the retracted lamp head.

I claim:

The ornamental design for a combination clock-radio and lamp, or similar article, substantially as shown.
